[57] **CLAIM**

The ornamental design for an editing device for copying machine, as shown and described.

DESCRIPTION

FIG. 1 is a front elevational view of an editing device for copying machine showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and

FIG. 7 is a right, front perspective view thereof, the broken line showing of a copier is environmental only and forms no part of the claimed design.
